UNITED STATES PATENT OFFICE

167,727

CLOTHESPIN

Albert R. Teare, Cleveland Heights, Ohio

Application July 24, 1951, Serial No. 16,001

Term of patent 14 years

(Cl. D17—6)

To all whom it may concern:

Be it known that I, Albert R. Teare, citizen of the United States, residing at Cleveland Heights, in the county of Cuyahoga and State of Ohio, have invented a new, original, and ornamental Design for a Clothespin, of which the following is a specification, reference being had to the accompanying drawing, forming part thereof.

In the drawing, Fig. 1 is a front view of a clothespin showing my new design, and Fig. 2 is a side view of the same.

I claim:

The ornamental design for a clothespin, as shown.

ALBERT R. TEARE.
